Patented May 24, 1960

188,020

HOLDER FOR COMBS AND BRUSHES

Arnold Cohen, 96-09 66th Ave., Forest Hills, N.Y., and Oscar Beder, 99-05 63rd Drive, Rego Park, N.Y.

Filed Oct. 26, 1959, Ser. No. 58,055

Term of patent 14 years

(Cl. D86—10)

Fig. 1 is a front perspective view of a holder for combs and brushes, showing our new design;

Fig. 2 is a rear perspective view thereof;

Fig. 3 is a side elevational view thereof;

Fig. 4 is a top plane view thereof; and

Fig. 5 is a vertical sectional view taken on the line 5-5 of Figure 4.

We claim:

The ornamental design for a holder for combs and brushes, substantially as shown.
